SOUND OPERATED CONTROL SYSTEM

Maxwell A. Kerr, Collingswood, N. J., assignor
to Radio Corporation of America, a corpora-
tion of Delaware

Application May 31, 1939, Serial No. 276,684

3 Claims. (Cl. 177—352)

This invention relates to control systems or apparatus such as are operated in response to sound, and has for its principal object the provision of an improved system and method of operation whereby the operation of various types of apparatus may be more effectively controlled in response to sound or to currents of audio frequency.

While the invention is illustrated as applied to a fog signal system for guiding ships, it is obvious that its essential features have many useful applications where a desired effect is to be produced in response to the blast of a horn or to sound from any other type of control source. Thus it may be utilized, for example, to switch a load device from the input to the output circuit of a vacuum tube amplifier, to control the operation of a public address system so that sound may be picked up at a desired point, and to control the operation of various other devices which it is desired to actuate in response to sound or to currents of audio frequency.

In its more specific aspects, the invention is illustrated as applied to a signal system which is set into operation in response to the sound of a ship's fog horn and functions to produce successive trains of sound impulses indicating the position of a lighthouse, a lightship, a buoy or the like. Such a signal system includes a microphone or sound pickup device which may also function as a sound reproducer, in which case the control system automatically switches the microphone from the input circuit of a control amplifier to the output circuit of a vacuum tube amplifier, vibrator-operated converter, motor-generator, or any other suitable alternating current source and vice versa.

Other features of the invention are (1) a vacuum tube amplifier which has its plate impedance and therefore its anode voltage varied in response to sound from the control source, (2) a control device which is triggered to pass current in response to a predetermined level of the amplifier anode potential, and (3) a relay which is operated in response to the control device current and functions (a) to disconnect the sound pickup device from the amplifier input circuit, (b) to complete the circuit of a sound reproducer, (c) to initiate operation of a clockwork-mechanism which functions to recycle the control amplifier after a suitable interval, and (d) to initiate operation of a tone generator in case the sound pickup is also utilized for producing the sound emanating at the lighthouse or other control station. Also included in the system are other con-

trol, calibration and protective features, herein-after described in detail.

The invention will be better understood from the following description considered in connection with the accompanying drawing, and its scope is indicated by the appended claims.

The single figure of the drawing is a wiring diagram of a fog signal system embodying the invention.

This system includes a pair of sound pickup devices or microphones 10 and 11 supplied with a continuous polarizing field by suitable permanent magnets mounted within them, the microphones being connected through contacts 12—13 and 14—15 of a relay operated switch 16 with the opposite end terminals 17 and 18 of the primary of an amplifier input transformer 19, the mid-terminal 20 of this primary being grounded at the terminal 21, together with the low voltage side of the microphones 10 and 11. These microphones are also arranged to be connected through leads 22 and 23 and a relay operated switch 24 to a tone generator 25 in case the microphones are utilized to produce the sound emanating at the control station and may be of any suitable type, such as that shown, for example, in the Hahnemann et al. U. S. Patent No. 1,667,418 or the Giannini et al. U. S. Patent No. 2,252,846. The generator 25 and switch 24 may be omitted if separate sound reproducers are provided, in which case such separate sound reproducers and their associated power sources are controlled through the terminals 26 and 27.

From the secondary circuit of the transformer 19, the control signal is applied through resistors 28 to 31 to the control grid 32 of an electron discharge type of amplifier and detector 33. This combined amplifier and detector is provided with an amplifier plate circuit which includes the anode 35 and the cathode 34, and with a detector circuit which includes the cathode 34 and the diode plates 36. As later described, the function of the detector is to apply to the amplifier input circuit a negative bias potential whereby the potential of the anode 35 is made more positive in response to sound received at the microphones 10 and 11.

Responsive to this variation in the direct current potential of the anode 35 are a pair of parallel-connected electron discharge devices 37 and 38, which are provided with control electrodes or control anodes 39 and 40 connected to the amplifier anode 35 through a resistor 41 and the upper right hand contacts 43—44 of a calibration switch 42. The input circuit of the control de-

vices 37—38 is, of course, completed through the cathode-anode circuit of the amplifier 33 and the ground terminal 21.

Beginning at the terminal 21, the cathode-anode or plate circuit of the control devices 37 and 38 includes the electron discharge path of these devices, a clockwork-operated switch 45, the operating solenoid 46 of the switch 16, and a positive power supply terminal 47 which may be maintained at a potential of the order of 135 volts. While the solenoid 46 is also connected through an adjustable resistor 48, the operating coil 49 of a protective switch 50—51, a calibration resistor 52, and the cathode-anode circuit of the amplifier 33 to the power supply source, it should be understood that the current of the coil 49 is sufficiently large to operate the switch 16 only when current is transmitted through the cathode-anode circuit of the devices 37 and 38, which are provided in duplicate merely for the purpose of increasing reliability in operation of the system.

The protective switch 50—51 is normally maintained in its open position by the plate current of the amplifier 33, and is operated to its closed position only in case the amplifier is rendered inoperative by failure of the tube or filament or plate battery, in which case the local sound signal is continuously operated in its normal cycle until the necessary repairs are made. To this end, the circuit of the operating coil 53 of the switch 24 is completed through the switch 50—51 to the ground terminals 21—26 on one side, and through the six-volt terminal 54 to the power supply source on the other side. Closure of the switch 24 connects the direct current input terminals of the generator 25 to the power source through the six-volt terminal 54, and the alternating current output terminals of the generator to the devices 10 and 11 through the leads 22 and 23.

Operation of the switch 16 to its upper closed position also completes the circuit of the operating coil 53 of the switch 24 through the parallel-connected or duplicate contacts 55—56 and 57—58 and, in addition, completes through the contacts 59—60 the circuit of a clockwork winding coil 61.

Included in the circuit of the clockwork winding coil 61 is a switch 62—63, which is so mechanically related or coupled to the switch 45 that the switch 45 is momentarily opened just before the switch 62—63 is closed, this result being effected through a mechanism including an operating member 64 which is biased to the closed position of the switch 62—63 by the clockwork operating spring 65.

The amplifier output terminals of the device 33 are connected through a capacitor 66 to the primary winding 67 of a transformer 68, through which they are coupled to the diode circuit of the device 33. Included in this diode or detector circuit are the secondary winding 69 and the resistor 31 which is also included in the amplifier input circuit and is shunted by a capacitor 70.

The resistor 29—30 and a capacitor 71 are provided for timing the rate of change in the potential of the amplifier anode 35. The time constant of the resistor 29—30 and a capacitor 71 is preferably several times greater than the time interval of the lowest audio frequency signal to be amplified. This time constant is adjusted to the required value by change in the movable contact position of the resistor 30. Resistor 41 and capacitor 71 also perform a similar function between the anode 35 of the amplifier

and the control anodes 39 and 40 of the control devices 37 and 38.

The inductor 72 and capacitor 73 are connected in shunt to the primary circuit of the amplifier input transformer 19, for the purpose of attenuating frequencies above 1000 cycles without appreciably affecting the response at lower frequencies. This is desirable in order to exclude the effect of sounds of frequencies outside the range of the usual ship's fog signal. Further attenuation of these undesired frequencies is produced by the capacitors 74, 75 and 76.

The function of the resistor 41 connected in the output circuit of the control devices 37 and 38 and the capacitor 71 is to attenuate sudden voltage surges or transients in the plate circuits of the amplifier before they reach the anodes of the control devices 37 and 38. This permits resetting of the amplifier by a momentary opening of the switch 45, for the reason that the voltage applied to the control electrodes of the devices 37 and 38 will not rise to the voltage of the amplifier anode 35 until the control devices 37 and 38 have had sufficient time to completely de-ionize before they are subjected to the normal standby voltage.

The calibration switch 42 is illustrated as in its normal position. In its lower or calibrating position the secondary winding of the transformer 19 is short-circuited through the contacts 78—79, and the input of the control devices 37 and 38 is interrupted at the contacts 43—44 and is completed through the contacts 44—80 to the right hand end terminal of the resistor 52.

With these connections, the amplifier plate voltage of the device 33 is adjusted by (1) shifting the movable contact to include less of the resistor 48 in the plate circuit until plate current starts through the device 37 or 38 and operates the sound reproducer, and (2) moving the switch 42 to its illustrated position. This adjustment leaves the amplifier output voltage at a value about 6 volts lower than that required to initiate operation of the control devices 37 and 38, and permits the system to be readily calibrated to compensate for decrease in the voltage of the power supply source, so that the system is always operated in response to the same range of signal intensities.

In the "stand-by" condition of the system, (1) the operating coil 46 is not sufficiently energized to operate the switch 16 to its upper position, (2) the clockwork-winding solenoid 61 is not energized, (3) the switches 45 and 62—63 are closed, (4) the protective switch 50—51 is open, (5) the calibration switch 42 is in its illustrated position, (6) the operating coil 53 of the switch 24 is not energized, and (7) no direct current is supplied to the generator 25.

When sound of the required frequency is picked up by the devices 10 and 11 for a period of time dependent on the adjustment of the resistor 30, (1) the potential of the anode 35 is raised, (2) higher potential is applied to the control electrode 39 and 40 of the control devices 37 and 38, (3) current starts through the cathode-anode circuit of one of these control devices, and (4) the switch 16 is operated to its upper closed position.

In this position of the switch 16, (1) the primary circuit of the amplifier input circuit is interrupted at the contacts 12—13 and 14—15, (2) the circuit of the operating coil 53 of the switch 24 is completed through the duplicate contacts 55—56 and 57—58, and (3) the circuit of the

clockwork winding solenoid 64 is completed through the contacts 59-60.

Operation of the switch 24 to its closed position connects the generator direct current input terminals to the 6-volt terminal of the power source and connects the alternating current output terminals to the microphones which then become reproducers or transmitters. With these connections, there is originated at the devices 10 and 11 sound of a tone dependent on the frequency of the generator 25.

It is desirable, however, that the local signal should continue in its normal train for a sufficient time to allow the passage of a ship and should then terminate. This result is accomplished by a clockwork mechanism which includes a pawl and ratchet device 91, 92 mechanically coupled to the control member 64 of the switches 45 and 62-63 in such a way that (1) switches 45 and 62-63 are closed during the stand-by period, (2) the clockwork spring 65 is wound sufficiently for one operating cycle in response to closure of the switch 16, (3) the switch 62-63 is opened in response to energization of the clockwork winding solenoid 61, and (4) switch 45 is momentarily opened, as by means of a cam device 93, to recycle the amplifier just before switch 62-63 is again closed. A suitable type of clockwork mechanism for this purpose is "Ford Motor Company Part No. 81A-15005-C" when modified by the addition of switch 45, or it may be of the type shown and described either in the Eaton U. S. Patent No. 455,873 or the Banks U. S. Patent No. 587,693.

A more detailed description of the operation of the device is as follows: When sound of the required frequency is picked up by the devices 10 and 11 a corresponding A.-C. potential is impressed on the primary winding of the transformer 19 through input terminals 85-86-21, the switch contacts 12-13 and 14-15, and the transformer primary terminals 17-18-20. The transformer 19 provides a proper impedance match and voltage step up between the microphones 10 and 11 and the high impedance input circuit to the amplifier tube 33. The potentiometer 28 functions as a sensitivity control for the amplifier 33. The amplified alternating current potential in the plate circuit of the amplifier 33 is coupled to the primary winding 67 of the transformer 68 through the capacitor 66, the majority of the A.-C. energy following the path through the capacitor 66 since this path has much lower impedance than the path formed by the calibrating resistor 52, the relay coil 49, the plate voltage adjusting resistor 48, the relay coil 46, and the 135-volt battery. The impedance of the resistor 41 and the capacitor 77 is also high with respect to the impedance of the capacitor 66 and the primary winding 67. The transformer 68 provides a voltage step up and impedance match between the plate circuit of the amplifying tube 33 and the principal diode load formed by the resistor 31 and the capacitors 70 and 75. The two diode plates 36 in the amplifier tube 33 are connected in parallel for added reliability. The principal function of the capacitor 75 is to aid in reducing the sensitivity of the system to frequencies above the normal frequency range of fog signals.

The A.-C. voltage from the secondary winding 69 of the transformer 68 is rectified through the diode portion of the tube 33 and produces a D.-C. potential across the resistor 31, the end of the resistor 31 which is connected to the winding 69 becoming negative with respect to the cathode

34 of the amplifier 33. This negative potential is impressed on the control grid 32 of the amplifier 33 through the timing resistors 29 and 30 and the sensitivity control resistor 28. The capacitor 71 and the resistors 29 and 30 perform two functions, namely, (1) they filter the pulsating D.-C. across the resistor 31 before it reaches the grid 32, and (2) they provide an adjustable time delay between the time the D.-C. potential appears across the resistor 31 and the time it is impressed on the grid 32. This time delay is important in preventing the detectors 37 and 38 from being triggered by sudden impulses of sound, such as a clap of thunder, a call of a bird, a rifle shot, or other random noises. It is thus necessary for the sound picked up by the microphones 10 and 11 to be sustained for two or more seconds in order to overcome the time delay caused by the resistors 29 and 30 and the capacitor 71. A ship's fog signal has this characteristic. The negative voltage impressed on the control grid 32 causes the plate impedance of the amplifier 33 to increase and thus decreases the plate current.

The D.-C. resistance of the solenoid winding 46, the resistor 48, the solenoid winding 49 and the resistor 52 produces a voltage drop between the terminal 47 of the power supply and the anode 35 of the amplifier 33 when plate current is flowing. As described heretofore, the amplifier 33 is calibrated by adjusting the potential of the anode 35 to a value which is a few volts below the potential required on the control anodes 39 and 40 of the devices 37 and 38 in order to trigger them.

A sustained sound signal picked up by the microphones 10 and 11 causes a decrease in the plate current of the amplifier 33, as described above. When the D.-C. resistance in the external plate circuit has not changed, a decrease in plate current will cause a decrease in voltage drop from the terminal 41 to the anode 35, and thus an increase in the plate potential between the anode 35 and the terminal 21 will result. This increase in plate potential is passed through the contacts 43-44 and the resistor 41 to cause the A.-C. voltage across the capacitor 77 to rise by the same amount after sufficient time has elapsed to overcome the time delay in the resistor 41 and the capacitor 77. When the D.-C. potential across the capacitor 77 has previously been adjusted to within a few volts of the amount required to trigger the control devices 37-38, this additional rise in voltage initiates a discharge between control anodes 39 and 40 and the cathodes 81 and 82 of the control devices 37 and 38, respectively. In turn, this initiates the main discharge between the main anodes 89 and 90 of the devices 37 and 38, respectively, and the cathodes 81 and 82.

The control devices 37 and 38 are similar to the RCA type OA4-G tubes or to the Western Electric type 313-C tubes, and the published data shows that with A.-C. potentials up to approximately 175 volts between the main anode and the cathode, no discharge will occur until the voltage between the control anode is raised to a value between 70 and 90 volts. The published data also shows that once this discharge is initiated, it will continue. The tube assumes a constant voltage drop of approximately 70 volts between the main anode and the cathode and continues to pass current until the plate supply voltage is lowered to less than 70 volts. The discharge through the tube then stops and remains stopped until the plate supply is increased and until an-

other discharge is initiated by the control anode. The clockwork functions to stop the discharge through the control devices 37 and 38 by momentarily opening the contacts 45, as heretofore described.

I claim as my invention:

1. In a combined signal receiving and signal transmitting system, the combination of an electro-acoustical converter adapted to convert sound into alternating current and vice versa, means for producing a potential in response to alternating current, means normally coupling said converter to said potential producing means whereby said potential producing means is responsive to the alternating current output of said converter, an alternating current signal generator, a control device coupled to said potential producing means and responsive to potentials produced thereby, said control device having a normally closed output circuit including a relay which is energized by the output of said control device when the potential applied to said device by said potential producing means has reached a predetermined value, means for maintaining said relay energized independently of the operating condition of said potential producing means, switching mechanism operable in response to said relay to disconnect said converter from said potential producing means and to connect said converter to said generator upon energization of said relay, and means rendered operative upon energization of said relay for restoring said relay after a predetermined time interval to effect operation of said switching mechanism to disconnect said converter from said generator and reconnect it to said potential producing means.

- 5 2. The invention set forth in claim 1 characterized in that said potential producing means comprises a vacuum tube amplifier, and characterized further in that said control device includes an electron discharge tube of the type which continues to discharge after being initially triggered, the input circuit of said discharge tube being connected to the output circuit of said amplifier and the output circuit of said discharge tube being connected to said relay, the operation of said discharge tube after being triggered causing said relay to become and remain energized.
- 10 3. The invention set forth in claim 1 characterized in that said potential producing means comprises a vacuum tube amplifier, characterized further in that said control device includes an electron discharge tube of the type which continues to discharge after being initially triggered, the input circuit of said discharge tube being connected to the output circuit of said amplifier and the output circuit of said discharge tube being connected to said relay, the operation of said discharge tube after being triggered causing said relay to become and remain energized, characterized further by the addition of a normally closed switch in the output circuit of said discharge tube, and characterized still further in that said means for opening said last named output circuit comprises a clockwork mechanism coupled to said switch and arranged to open said switch at the expiration of said predetermined time interval.
